(57) **CLAIM**

The ornamental design for a venetian blind slat having elongated inner cord holes, as shown and described.

DESCRIPTION

FIG. 1 is a perspective view of the venetian blind slat having elongated inner cord holes;

FIG. 2 is a front view of the venetian blind slat having elongated inner cord holes. The rear view of the venetian blind slat having elongated inner cord holes is a mirror image of the front view shown in FIG. 2;

FIG. 3 is a top view of the venetian blind slat having elongated inner cord holes. The bottom view of the venetian blind slat having elongated inner cord holes is a mirror image of the top view of FIG. 3; and,

FIG. 4 is right side view of the venetian blind slat having elongated inner cord holes. The left side view of the venetian blind slat having elongated inner cord holes is a mirror image of the right side view of FIG. 4.
